United States Patent Office.

WILLIAM TANSLEY, OF SALISBURY CENTRE, ASSIGNOR TO "STARBUCK BROTHERS," OF TROY, NEW YORK.

Letters Patent No. 97,989, dated December 14, 1869.

IMPROVEMENT IN BARK-MILLS.

The Schedule referred to in these Letters Patent and making part of the same

To all whom it may concern:

Be it known that I, WILLIAM TANSLEY, of Salisbury Centre, in the county of Herkimer, and State of New York, have invented certain new and useful Improvements in Bark-Mills; and do hereby declare the following to be a full, clear, and exact description thereof, reference being had to the accompanying drawings, making part of this specification, and in which—

Figure 1 is a side elevation of my improved mill;

Figure 2, a vertical section through the centre of the same;

Figure 3, a top view of the same;

Figure 4, a side view of the runner and shaft; and

Figure 5, a central vertical section of the runner.

The object of my improved mill is to so arrange the grinders or graters on both the revolving and stationary parts of the mill, one above the other, that the bark, coarsely ground by the upper, is discharged directly into the lower grinding-surfaces, where it is reground to the requisite fineness, and more evenly than has heretofore been done, where the bark required rehandling before being finished.

To enable those skilled in the art to make and use my improved mill, I will proceed to describe the same, referring by letters to the drawings, similar letters denoting like parts in the several views.

A represents the curb of the mill, provided at top and bottom with ears c, for the purpose presently explained.

This curb has what I will designate a core, M, and the interior face of the curb proper and exterior face of the core are serrated, or provided with grinding-teeth, in two sets, the faces being divided longitudinally, the upper set C being coarse, and the lower one, D, fine; the teeth of the former having a pitch of about one inch and an eighth, and the latter, a pitch of about a half inch.

The core M is held in position, and leaving an annular space between it and the interior face of the curb proper, by means of arms E.

The core is hollow, and has arranged therein centrally a hollow bearing, L, for the purpose hereinafter specified.

F is the runner, formed of two concentric conical rings, the base of the upper resting on the apex of the lower. The inner and outer peripheries of both are serrated or fluted to correspond with the two sets of grinding-teeth on the core M and the curb A.

The apex of the upper cone of the runner is cut away, forming a series of steps 1, 2, 3, &c., the said steps projecting about equal to the pitch of the teeth, and dropping about three-quarters of an inch to the step, the number of steps depending upon the size of the runner, a base-ring being left for support.

The base of the lower cone is provided with arms G, G, &c., merging at the centre, and forming a bearing, through which the shaft B passes, and projecting downward a short distance, forming stops, against which the driver J comes in contact, as will be presently explained, and extending upward a short distance, and forming a ring, K, which fits into the hollow bearing L of the core M.

The shaft B passes up through the shoulders of the arms a, (which are secured to the lower side of the curb, at the ears c, and support the same in a fixed position,) through the ring K, and up through the centre of the core M, and is provided with a suitable bark-breaker, O, which is secured to the shaft by means of a feather.

To the lower part of the shaft B, and the proper distance from the end, is cast, or otherwise secured thereon, a driver, J, which, when the shaft is in position, is interlocked between the shoulders H of the arms G, so that the rotation of the said shaft produces a similar movement of the runner F.

The ring or annular journal K, fitting up into the central hollow bearing L, keeps the stationary and revolving parts true, one with the other.

A hopper may be attached to the top of the curb, to the ears c, by means of bolts.

The formation of the steps, on the apex of the upper cone of the runner hereinbefore mentioned, provides grippers, which, when the runner is in motion, grasp the bark, and drag it into the space between the grinding-surfaces, and force it down.

I am aware that bark-mills have been heretofore constructed with concentric conical rings, forming an inside and outside or double grinding-surface.

I am also aware that mills have been made, having one runner above another, each runner acting independently of, and discharging its grindings at a different outlet from the other. I do not wish to claim any of these features; but having described the construction and operation of my improved mill,

What I claim as new, and desire to secure by Letters Patent, is—

1. Constructing the upper conical ring of the runner with a series of steps, supported on a continuous concentric base, and provided with interior and exterior grinding-teeth, substantially in the manner and for the purpose set forth.

2. In combination with the above, the upper and lower grinding-surfaces C and D, one directly over the other, the upper discharging the coarsely-ground material into the lower, substantially in the manner and for the purpose set forth.

3. The central hollow bearing L of the core M, in combination with the ring or annular journal K, arms G, (having stops H,) and shaft B, with the

driver J, all constructed and operating substantially as described, for the purpose set forth.

4. In bark or other mills, the combination and arrangement of the upper and lower continuous grinding-surfaces, the base of the former resting upon and slightly projecting over the top of the latter, grinding coarsely and evenly, and discharging into the

lower, where the bark is finely ground and finished, substantially as and for the purpose set forth.

In testimony whereof, I have hereunto set my hand, this 18th day of August, A D. 1869.

Witnesses:

L. D. GILMAN,
FRANK H. RICHARDS.
